FAN CONSTRUCTION

Arthur F. O'Connor, Chicago, Ill., assignor to
 Union Asbestos & Rubber Company, a corpora-
 tion of Illinois

Application November 3, 1945, Serial No. 626,505

7 Claims. (Cl. 230—42)

1

This invention relates to fan constructions and more particularly to air circulating fans of the type used in railway refrigerator cars and the like.

For railway refrigerator car uses, the fan is normally driven by a power take-off mechanism operated from the car wheel, so that the fan must be able to deliver air in the desired direction regardless of the direction of fan rotation. It is furthermore desirable that fans of this type be controllable so that the direction of air delivery can be reversed to accommodate different operating conditions, as, for example, when the car is used as a ventilated car. It is one of the objects of the present invention to provide a fan construction which satisfies all of these requirements.

Another object is to provide a fan construction in which the direction of air delivery can be controlled by turning a housing or shroud around the fan blades.

Still another object is to provide a fan construction in which the housing is rotatably supported on the main fan shaft and can be turned through a rack and pinion mechanism.

A further object is to provide a fan construction formed in a hollow beam adapted to support or to provide a part of the lading floor of the car and in which the fan can be controlled to circulate air in either direction through the beam.

A still further object is to provide a fan construction including a plurality of fan units simultaneously controllable to reverse the direction of air circulation.

The above and other objects and advantages of the invention will be more readily apparent from the following description when read in connection with the accompanying drawing, in which—

Figure 1 is a top plan view of a fan construction embodying the invention, with parts in section; and

Figure 2 is a transverse section taken centrally through one of the sets of fan blades of Figure 1.

The construction illustrated in the drawing comprises a hollow box-like beam having a bottom plate 10 and a top plate 11 connected to the bottom plate and supported thereon by a series of transverse webs 12. As shown, the top plate has side flanges turned down at the opposite edges thereof, the lower edges of which are connected by guide plates 13 to the under part of the top plate. The beam, as shown, may be of the same height as the floor or lading rack in a refrigerator

2

car, to form a part of the rack or to act as a support for the rack.

The fan construction proper comprises an elongated shaft 14 extending centrally through the beam and driven by a pulley 15. The shaft may be supported on pillow blocks or, as shown, on bearings 16 in the ends of the beam and in the webs 12. At spaced points in its length the shaft 14 carries hubs 17 which are rigidly secured to the shaft and each of which supports a set of radially-extending blades 18.

To control the direction of air discharge by the blades 18, a housing or shroud is provided comprising an arcuate plate 19 substantially semi-cylindrical and of a length to encircle approximately half of the periphery of the blades. At its edges the plate 19 may be turned down to form side flanges 21 partially overlying the ends of the blades. The shroud or housing 19 is supported for rotation about the shaft 14 by means of collars 22 rotatably encircling the shaft and connected to the housing by rods or bars 23. With this construction the housing may be turned freely about the shaft so that the open side of the housing may register selectively with one or the other of the open sides of the beam. Movement of the housing is preferably limited by a fixed stop 24 carried by the bottom plate 10 to engage one end or the other of the housing, thereby to insure proper positioning of the housing to discharge air through one side or the other of the beam.

To turn the housing an annular rack 25 is secured to one side thereof and is adapted to mesh with a pinion 26, slidably supported on a control shaft 27 which may be a square or of other non-circular section. The control shaft extends through the beam at one side of the fan housing and is rotatably supported in brackets 28 in the beam by means of thimbles 29, slidably engaging the shaft and rotatable in the brackets. The pinions 26 are urged against the housings and into mesh with the racks by springs 31 seating against the pinions and thimbles 29. These springs press the pinions against the sides of the housings and urge the housings axially of the shaft so that one of the collars 22 will engage one end of the hub 17 properly to position the housing relative to the sets of fan blades. The shaft 27 may be turned through any desired control mechanism such as a shaft extending through the side wall of the car to carry a hand wheel and operating gearing engaging a pinion 32 on one end of the shaft.

In operation with the housing turned to the

position shown in Figure 2, air will be drawn in from one side of the beam around the ends of the housing and axially into the fan blades. The housing will direct the air so that the blades will discharge it through the left side of the beam, creating the circulation in the car from the right to the left of the beam. To reverse the direction of air circulation, the shaft 21 may be turned simultaneously to turn the several fan housings through the pinions 26 so that the left sides of the blades will be enclosed and the right sides will be open. At this time, the air will be circulated in the same manner from the left to the right side of the beam.

While one embodiment of the invention has been shown and described in detail, it will be understood that it is illustrative only and is not intended to be a definition of the scope of the invention, reference being had for this purpose to the appended claims.

What is claimed is:

1. A fan construction comprising a rotatable shaft, a set of substantially radial blades on the shaft, a substantially semi-circular housing partially encircling the blades, means mounting the housing for rotation about the shaft axis, an arcuate rack carried by the housing, a control shaft extending adjacent the housing, a pinion slidable on the control shaft, and a spring urging the pinion toward the housing to mesh with the rack.

2. A fan construction comprising a hollow beam having closed top and bottom and open sides, a rotatable shaft extending lengthwise centrally through the beam, a hub on the shaft, a set of substantially radial blades carried by the hub, a substantially semi-circular housing partially encircling the blades and leaving a peripheral opening through which air is forced by the blades, said housing being open at its ends to provide air inlets, means including collars around the shaft adjacent the ends of the hub rotatably to support the housing, and means to turn the housing around the shaft to control the direction of air delivery by the blades.

3. A fan construction comprising a rotatable shaft, a hub on the shaft, a set of substantially radial blades carried by the hub, a substantially semi-circular housing partially encircling the blades and leaving a peripheral opening through which air is forced by the blades, means including collars around the shaft adjacent the ends of the hub rotatably to support the housing, an arcuate rack secured to the housing, a control shaft extending adjacent the housing, a pinion slidable on the control shaft, and a spring urging the pinion toward the housing to mesh with the rack and urging the housing to a position in which one of the collars engages an end of the hub.

4. A fan construction comprising a hollow beam having a closed bottom, a closed top and open

sides, a rotatable shaft extending lengthwise centrally through the beam, a hub on the shaft, a set of substantially radial blades carried by the hub, a substantially semi-circular housing extending partially around the blades having an open side to register selectively with the open sides of the beam, the housing being open at its ends to provide air inlets, means mounting the housing for turning in the beam about the axis of the shaft, and control means carried by the beam to turn the housing.

5. A fan construction comprising a hollow beam having open sides, a rotatable shaft extending lengthwise centrally through the beam, a hub on the shaft, a set of substantially radial blades carried by the hub, a substantially semi-circular housing extending partially around the blades having an open side to register selectively with the open sides of the beam, means including collars rotatably supported on the shaft adjacent the ends of the hub to support the housing for turning about the axis of the shaft, a control shaft extending through the beam adjacent the housing, a pinion slidable on the control shaft, and a spring urging the pinion toward the housing to mesh with the rack and urging the housing to a position in which one of the collars engages an end of the hub.

6. A fan construction comprising an elongated hollow beam having open sides, an elongated shaft extending centrally through the beam, a plurality of spaced hubs carried by the shaft, a set of substantially radial fan blades carried by each of the hubs, a housing having one open side rotatably mounted around each set of blades, the housing opening at their ends into the spaces between the sets of blades, and means for simultaneously turning the housings.

7. A fan construction comprising an elongated hollow beam having open sides, an elongated shaft extending centrally through the beam, a plurality of spaced hubs carried by the shaft, a set of substantially radial fan blades carried by each of the hubs, a housing having one open side rotatably mounted around each set of blades, arcuate racks carried by the housings, a control shaft extending through the beam, and pinions on the control shaft meshing with the racks for turning the housings simultaneously.
